UNITED STATES PATENT OFFICE.

NEWTON I. STEERS, OF WILMINGTON, DELAWARE, ASSIGNOR TO E. I. DU PONT DE NEMOURS & COMPANY, OF WILMINGTON, DELAWARE, A CORPORATION OF DELAWARE.

BLASTING CAP.

Application filed February 16, 1924. Serial No. 693,204.

To all whom it may concern:

Be it known that I, NEWTON I. STEERS, a citizen of the United States, and a resident of Wilmington, in the county of New Castle 5 and State of Delaware, have invented a certain new and useful Blasting Cap, of which the following is a specification.

This invention is in the art of explosives, and has particular relation to blasting caps, 10 and, strictly, to the shell of such a cap. The shell is loaded with a sensitive and violent explosive, e. g. fulminate of mercury, and in use a fuse is inserted in the open end of the loaded shell, or cap, and the cap is placed 15 in close relation to a charge of high explosive to be detonated; the explosion of the cap gives the shock and heat necessary to cause detonation of the charge. These matters are of course well understood in the art; 20 but for present purposes it is to be noted that upon the explosion the material of the shell becomes mingled with the material being blasted. The present invention has to do with the overcoming of the difficulties 25 which this mingling entails.

Heretofore copper shells have been in almost universal use for blasting caps, since not only is copper readily available and easily drawn but also, and primarily, it is not attacked by the action of the free mercury of the fulminate. Yet a great disadvantage of the copper shell is that its finely divided particles or compounds therefrom contained in the material blasted down cause discoloration 35 of the material, when such material is, say, treated in chemical processes. A notable instance of this is in the mining of fine clays for high-grade pottery: the presence of copper in this clay causes objectionable discoloration of the finished product. Again, owners of soft mines object to the copper. I have devised a blasting cap which overcomes difficulties and faults such as those indicated.

One object of the invention is to provide 45 a blasting cap and shell the particles of which will not have a deleterious effect on the material blasted, but yet the shell will satisfactorily resist the action of material with 50 which the shell is loaded, e. g. the free mercury in fulminate, and at the same time will be composed of readily available, easily workable and inexpensive materials. To

this end, and also to improve generally on articles of the character indicated, the invention consists in the various matters herein-after described and claimed.

Without restricting the invention thereto, I describe the same with more particular reference to the embodiment thereof illustrated 55 in the accompanying drawing, in which Figure 1 is an elevational diametrical cross-sectional view, and Figure 2 a simple cross-sectional view on the line 1—1 and the line 2—2 of Figures 2 and 1, respectively. For 60 simplicity, in Figure 1 the explosive is but partially shown, and no attempt is made in the figures to accurately indicate the relative thicknesses of the shell proper and the liner.

In accordance with the invention I make the shell with a plurality of walls, as 1 and 2. Of these, the outer wall is of material of the necessary strength, but, as distinguished from copper, is such that it will not cause discoloration of the blasted materials. For example, it is a metal which will not oxidize readily or whose compounds are not such as will cause discolorations. I have found that 65 aluminum meets these requirements in a 70 highly satisfactory manner; and, too, it is cheaper and lighter than copper, and is readily worked, e. g. drawn. The inner wall 2 is of a material which will withstand the action of the explosive 3, that is, as a practical matter in present day practice, it is a 75 material which will withstand the action of the free mercury in fulminate of mercury, and is also one which will not cause discoloration as aforesaid. Desirably it is of tin, 80 although it may be of lead or other suitable material. As is evident, in referring to the inner wall being "explosive resistant" "with- 85 standing the action of the explosive," and the like, I have reference to the ability of 90 the wall to withstand the chemical or like attack of the explosive or certain of its 95 ingredients, rather than to ability to withstand the shock of the explosive.

It is to be particularly noted that, as 100 illustrated by the example given (aluminum and tin) the invention permits of, and provides for, the selection of a material for the outer wall with primary consideration for its non-discoloring properties and strength, 105 without having to consider its ability to

resist the action of the explosive, since this resistance is furnished by the inner wall; also it provides for the selection of property resistant material without having to consider its strength. Thus the invention provides a shell which will not cause discoloration and yet is of the proper strength and explosive resistant qualities, and, specifically, provides a shell which, while having the desirable features of copper, has not the disadvantages of copper.

Desirably, and as conventionally shown, the major portion of the shell is provided by the relatively thick strength-giving wall 1, while the resistant wall 2 may be but relatively thin, having the character of a liner. For example, in a shell 1.5 inches long and having an outside diameter of .274 inch and an inside diameter of .220 inch, the aluminum outer wall may be .020 inch thick and the tin liner .007 inch.

The shell can be made in any desired way. For example, if both the inner and the outer shell are of ductile metal they may be drawn together. Or the shells may be made separately and the inner tightly fitted into the outer. While I have made particular reference to aluminum and tin it will be understood that the invention is not restricted thereto. For example, the outer shell may be made from metals other than aluminum and having the desired characteristics; and the inner wall may be made from any metal or combination of metals having the characteristics desired for that wall, also hard rubber, pyroxylin plastic and similar materials may be used.

The shell may be also made from a sheet of aluminum which has been tin plated or from other plated metals.

I claim:

1. A blasting cap shell comprising a strength-imparting wall of strong non-dis-

coloring material, and an inner explosive-contacting wall of non-discoloring material of a character to withstand the action of the explosive to be received in said shell.

2. A blasting cap shell comprising a pair of shell units the one received within the other to form a liner for such other, the units being of non-discoloring materials, and that of the liner being explosive-resistant.

3. A blasting cap shell comprising a plurality of walls of non-discoloring material, the material of the inner wall being such as to withstand the action of the free mercury in fulminate.

4. A blasting cap shell of non-discoloring materials having a laminated wall, the inner lamination of the wall being of a character to withstand the action of the explosive to be received in said shell.

5. A non-discoloring blasting cap shell of laminated structure, the inner surface of the shell being of a character to withstand the action of the explosive to be received in said shell.

6. A blasting cap shell comprising an inner explosive-contacting wall of tin and a surrounding wall of aluminum.

7. A blasting cap comprising a shell and explosive received in said shell, said shell comprising a strength-imparting wall of strong non-discoloring material, and an inner wall of non-discoloring material of a character to withstand the action of said explosive.

8. A blasting cap comprising an outer wall of aluminum, a liner of tin for said wall, and a charge of mercury fulminate in the shell and separated from said outer wall by said liner.

In testimony whereof I affix my signature.

NEWTON I. STEERS.

Certificate of Correction.

It is hereby certified that in Letters Patent No. 1,518,611, granted December 9, 1924, upon the application of Newton I. Steers, of Wilmington, Delaware, for an improvement in "Blasting Caps," an error appears in the printed specification requiring correction as follows: Page 1, line 41, for the word "soft" read *salt*; and that the said Letters Patent should be read with this correction therein that the same may conform to the record of the case in the Patent Office.

Signed and sealed this 6th day of January, A. D. 1925.

[SEAL.]

KARL FENNING,
Acting Commissioner of Patents.
